CONE ANCHOR

Filed June 27, 1927

By:

Inventor:
Albert B. Chance
Williams, Bradbury,
McClellan & Keable
Atty's.

UNITED STATES PATENT OFFICE

ALBERT B. CHANCE, OF CENTRALIA, MISSOURI

CONE ANCHOR

Application filed June 27, 1927. Serial No. 201,625.

The present invention relates to cone anchors and is more particularly concerned with the provision of an improved anchor adapted to be planted or imbedded in the soil for anchoring guy rods for telephone poles and the like.

One of the objects of my invention is the provision of an anchor of the class described which is adapted to be constructed with a minimum of material, but which possesses maximum strength and which is adapted to resist displacement both by the combined weight of the soil above it and by the formation of a compact ring of sub-soil above and about the outer edge of the anchor and adjacent the hole made for the anchor.

Another object of my invention is the provision of an anchor of the class described which is more durable, more economical and more efficient than the anchors of the prior art, and which comprises an upper portion having a smooth outer surface of the shape of the frustum of a cone or pyramid adapted to wedge apart the rocks or other bodies surrounding the anchor, forming a compact ring of material above and outside the outer edge of the lower portion of the anchor, which is of the shape of a frustum of less angularity than the frustum of the upper portion.

Other objects and advantages of my invention will appear more fully from the following description and from the accompanying drawings in which similar characters of reference indicate similar parts throughout the several views.

Referring to the drawings:—

Fig. 1 is a cross-sectional view of an anchor installation showing my improved anchor.

Fig. 2 is a medial cross-sectional view of my anchor with the guy rod.

Fig. 3 is a bottom plan view of the same, without the guy rod.

Fig. 4 is a plan view of a modified anchor.

Referring to Fig. 1, 10 indicates in its entirety the anchor installation which comprises a guy 11, of wire or cable, a guy rod 12 and an anchor 13. The guy rod 12 comprises an elongated rod having an eye 14 formed at its upper end for connection to the

cable 11, and having a threaded lower end 15 adapted to receive a nut 16^a.

The anchor 13, which I have termed a cone anchor, may be of the shape of a plurality of superposed frustums of cones, or a plurality of superposed frustums of pyramids, or a combination of the frustum of a pyramid and a cone, and wherever I employ the term cone throughout this specification and in the claims I use it in the generic sense covering both members of strictly conical shape and members of approximately conical shape having a plurality of plane sides like a pyramid.

The anchor 13 comprises an upper portion 16 which has an exterior surface of the shape of the frustum of a cone or pyramid of rather steep slope. The portion 16 of the anchor, which I shall term the wedging portion, is preferably formed with a smooth finished outer surface so that it is adapted to slide against rocks or other small bodies adjacent the anchor and wedge them in a lateral direction. The upper surface 17 of the anchor may be flat and of but slightly larger size than the guy rod 12.

The lower and outer portion 18 of the anchor is preferably formed like the frustum of a cone or pyramid of relatively less slope than the wedging portion 16, and this portion of the anchor may be termed the retaining portion as distinguished from the wedging portion. It should be noted, however, that all portions of the anchor are finally brought into play to retain the anchor imbedded in the soil, but that the outer ring of the anchor is adapted to provide a large part of the resistance.

The interior 19 of the anchor may be of similar form to the wedging surface 16, comprising a surface like that of the frustum of a pyramid, extending from the base of the anchor to a point 20 considerably below the top surface 17. There is thus provided an addition bulk of material near the top of the anchor for the purpose of supporting the load placed upon the anchor by the guy rod 12 and the nut 16. The anchor may be provided with a substantially square aperture 21 adapted to receive the nut 16^a and to seat the nut so that the guy rod may be readily thread-

ed into the nut without the use of wrenches. The upper end of the anchor is, of course, provided with a bore 22 adapted to receive the guy rod 12, and the anchor may be constructed of metal which is cast to the shape shown. The outer wedging surface 16 should, however, be finished to a smooth surface for the reasons previously stated.

The method of installation of my anchor is as follows. A hole 23 is bored into the soil substantially on a line with the top of the telephone pole or post to which the guy 11 is to extend. The anchor 13 is attached to the guy rod 12 by means of a nut 16^a and the anchor is placed in the bore in the earth. Sufficient broken stone is then placed upon the upper surface of the anchor to extend above the surface 17 and this stone may be tamped in order to compact the stone into position. During this tamping the wedging surface 16 serves to deflect the stone outward against the walls of the hole, after which the hole may be filled up with earth or other material to the top and tamped again if desired.

The guy wire 11 may then be attached to the eye 14 or to suitable tightening apparatus and the guy wire pulled taut, tending to draw the anchor 13 upward out of the hole 23. During this procedure the wedging surface 16 of the cone acts like a wedge against the rock, stone, or other bodies adjacent thereto, these bodies sliding on the smooth wedging surface and being forced into compact engagement with the outer walls of the hole 23. It is found that the compacting action of my anchor extends beyond the stone which is used for filling above the anchor, providing a compact ring of material above the outer ring 18 of the anchor and extending into the wall of the hole 23.

The outer ring 18, being of less slope or angularity, is adapted to react against this outer ring of compact material, providing a resistance to the upward movement of the anchor which does not depend alone upon the weight of the material above the anchor, but which brings into play the weight of all of the surrounding soil against which the compact ring of soil reacts.

It will thus be observed that by providing a smooth and steep wedging surface my anchor is adapted to compact the filling into firm engagement with the outer walls of the hole in such manner that the outer ring of the anchor may bear against the compacted portion to retain the anchor in place. By constructing my anchor with a hollow interior of the shape of a single frustum, I am enabled to provide an anchor which is light in weight and which has an excess of material about the lower portion, making the thickness of the lower ring 18 such that this ring, which bears a large portion of the weight, is of a greater strength than the upper portion

of the cone. Extensive tests made with anchors of the type described show that the retaining power of my anchor is far greater per unit weight of material used and for the size or projected area of the anchor than in 70 the anchors of the prior art.

It will thus be observed that I have provided an anchor having an exterior surface which may be formed like the surface of a plurality of superposed frustums of cones 75 or pyramids and that my anchor is provided with a wedging surface of one angularity and a retaining surface of a lesser angularity in such manner as to provide an anchor of the maximum retaining power with the minimum 80 of material.

While I have illustrated and described a specific embodiment of my invention, many modifications may be made without departing from the spirit of the invention, and I do 85 not wish to be limited to the precise details of construction set forth, but desire to avail myself of all changes within the scope of the appended claims.

Having thus described my invention, what 90 I claim is new and desire to secure by Letters Patent of the United States is:

1. In an anchoring device for guy wires and the like, the combination of a metal member having an upper portion of the shape of a frustum of relatively steep slope with a smooth outer surface and a lower outside portion of the shape of a frustum of less slope, said member having a tension member axially attached to said member, whereby said upper portion is adapted to wedge a filling against the walls of a hole to form a compact ring of filling above said lower portion, and the said lower portion of said member is adapted to exert a substantially less wedging effort on said filling than the wedging effort exerted by the said upper portion.

2. In an anchoring device for guy wires and the like, the combination of a metal member having an upper portion of the shape of a frustum of relatively steep slope with a smooth surface and a lower outside portion of the shape of a frustum of less slope, said member having a tension exerting member axially attached to said member, said upper portion being of such a slope as to wedge a filling against the walls of a hole to form a compact ring of filling above said lower portion, and said lower portion being of such a slope as to wedge the material adjacent the said lower portion in such a manner as to create lines of force inclined toward the walls of the hole.

In witness whereof, I hereunto subscribe my name this 21st day of June, 1927.

ALBERT B. CHANCE.
